UNITED STATES PATENT OFFICE.

IRWIN A. SEIDERS, OF READING, PENNSYLVANIA.

STEAM SUPERHEATER FOR LOCOMOTIVES.

Application filed April 14, 1924. Serial No. 706,294.

My invention relates to locomotive boilers and has for its object to provide an improved steam superheater construction for such boilers especially designed to provide 5 an exceedingly simple construction of superheater headers which can be cast preferably in two pieces and with little or no loss in the foundry. The entire advantage which I have in view is a material shortening 10 of the end extensions of the superheater tubes and my construction also makes it practicable to use but two sizes or at most but three sizes of superheater tubes. Still another advantage of my construction is 15 that it enables the superheater tube ends to be removed independently, that is to say, any one of the units in my superheater construction can be removed without requiring the removal of any others. Still another 20 advantage which I have in view is a material shortening in the steam pipes leading from the superheater to the cylinders and a construction of this part of the apparatus which is simpler than the constructions heretofore used, and still another advantage of 25 my construction lies in the provision of an exceedingly simple clamp for holding the ends of the superheater tubes in contact with the headers.

30 The nature of my improvements will be best understood as described in connection with the drawings in which they are illustrated and in which—

Figure 1 is a sectional elevation of the 35 front end of a locomotive embodying my improvements, the section being taken as on the line 1—1 of Fig. 3.

Figure 2 is a cross sectional elevation on the line 2—2 of Fig. 1.

40 Figure 3, a cross sectional elevation taken partly on the line 3—3 and partly on the line 3^a—3^a of Fig. 1.

Figure 4 is a front elevation of the sectional plates secured to the front of the 45 front header, as shown in Fig. 1.

Figure 5 is a section on the line 5—5 of Fig. 4.

50 Figure 6 is a sectional view showing the ends of a superheater unit secured in place on the header sections by means of the forked clamp which I prefer to employ, and

Figure 7 is a cross section on the line 7—7 of Fig. 6.

55 A indicates the shell of the boiler and A' the tube sheet secured to the front end of the shell. B, B, etc. are the usual small di-

ameter fire tubes extending through the boiler front tube sheet to the back tube sheet and, in accordance with my invention, disposed in concentric arcs, the flues B² being 60 staggered in arrangement with reference to the tubes B¹ and the inner tubes B³ of which, in the construction illustrated, there are but three, being staggered with reference to the tubes B². C, C, etc. are the super- 65 heater tubes, the ends C' of which extend at an angle to the body of the superheater tubes so as to make the connection with the headers as will be hereafter described. By preference, these superheater tube ends are 70 provided with spherical heads, as indicated at C². D is the steam pipe leading from the steam dome of the locomotive, not shown, and connecting through the joint F with the steam pipe E² connected with the rear header, indicated at E. E¹ is the front header. The two headers E and E¹ are of 75 arc shaped form and preferably nearly circular, as shown, being supported on brackets G, G, secured to the lower part of the 80 front end of the boiler shell. The front and rear headers are preferably cast separate from each other and secured together by bolts, as indicated at E⁴. From the lower portions of the front header at points be- 85 low the center line of the boiler I provide steam pipes indicated at E³, E³, which may and should extend out horizontally from the header as it is shown in Fig. 1, to a point in front of the screen P; connected with the 90 front end of these pipes E³ are the curved pipes e³ which lead to the cylinders not shown.

Joints are made between the header section and the ends C¹ of the superheater tubes, as best shown in Figs. 6 and 7. The spherical heads C² abut against seats at the outer ends of the parts indicated at e and e¹ in the front and rear headers and are abutted against seats H, H, which are supported on a forked clamping plate I, having forked ends, as indicated at I¹ and secured in place by a bolt J, extending between the abutting faces of the headers, as shown in Figs. 1 and 6.

K is the shell of the smoke box of the locomotive, and L, L¹, L², L², are sectional plates secured to the front header, as shown. The plates L¹ and L², L², are readily removable to permit of the withdrawal and insertion of superheater ends. M indicates a 100 damper, the pivot units of which are hinged 105

on the inner edges of the plates L^2 and connected through a connection indicated at M^1 . N is the upper member of a box like structure extending from the front of the plates L^1 , L^2 , supporting, as shown, a breaker, as indicated at O and a screen indicated at P . K^2 is the usual exhaust pot, K^1 the stack and K^3 the usual mixing nozzle. Q is a plate secured on the brackets G and extending back to the tube sheet A^1 , a certain number of the small tubes B lying below it, while the space lying above the plate Q and within the headers E , E^1 , forms a flue which is controlled by the damper M . R and R^1 are the usual screens.

It will be obvious that the illustrated construction provides in the arc shaped headers E and E^1 exceedingly simple castings and, by reason of the extension of these headers into the lower part of the boiler shell, makes it feasible to employ short steam pipes E^2 . It will also be obvious that the arc shaped suspension of the superheater flues B^1 , B^2 , B^3 , and the staggering of these flues with reference to each other makes it feasible to employ superheater units C with end extensions C^1 of only three sizes, and, where only two concentric rows of superheater flues are employed, of only two sizes, and it also makes it feasible for the superheater tube ends to extend in approximately radial planes to their points of connection with the superheater headers, so that each superheater end can be independently removed without necessitating the displacement of any other. The coupling of the superheater tube ends to the header sections by the forked plates I , as shown in Fig. 6, makes it very simple to connect or disconnect these parts and to permit the re-dressing or re-grinding of the spherical head C^2 . Where this is necessary, the removably sectional plates L^1 , L^2 , L^2 , when removed, give access to the individual superheating ends in a convenient and effective manner and these plates, in connection with the plate Q and the headers, form a flue, the flow through which is controlled by the damper M , so that when the engine is not using steam, a flow of furnace gases through the super-

heater flues can be cut off so as to protect the superheater tube ends from superheating.

Having now described my invention, what I claim as new and desire to secure by Letters Patent, is:

1. In combination with a locomotive boiler, superheater flues extending longitudinally through the boiler and arranged in concentric circular arcs, arc shaped superheater headers of greater diameter than the outer row of superheater flues secured in front of the boiler and superheater tubes extending into the flues and having laterally extending end extensions secured to the headers.

2. In combination with a locomotive boiler, superheater flues extending longitudinally through the boiler and arranged in concentric circular arcs, arc shaped superheater headers of greater diameter than the outer row of superheater flues secured in front of the boiler and extending down on each side thereof below the center line of the boiler, superheater tubes extending into the flues and having lateral end extensions secured to the headers and steam pipes connected to the lower portions of the outer headers.

3. In combination with a locomotive boiler, concentric rows of superheater flues arranged in staggered relation to each other, arc shaped superheater headers, concentric with but of greater diameter than the rows of flues, secured in front of the boiler and superheater tubes extending into the flues and having lateral end extensions connecting them with the headers in approximately radial lines.

4. In combination with a locomotive boiler, concentric rows of superheater flues arranged in staggered relation to each other, arc shaped superheater headers each forming a separate unit, concentric with but of greater diameter than the rows of flues, secured in front of the boiler and superheater tubes extending into the flues and having lateral end extensions connecting them with the headers in approximately radial lines.

IRWIN A. SEIDERS.
